UNITED STATES PATENT OFFICE.

ARCHIBALD BANNATYNE, OF WATERBURY, CONNECTICUT, ASSIGNOR TO
THE WATERBURY CLOCK COMPANY, OF SAME PLACE.

DESIGN FOR A CLOCK-DIAL.

SPECIFICATION forming part of Design No. 18,264, dated April 24, 1888.

Application filed May 3, 1887. Serial No. 237,013. Term of patent 7 years.

To all whom it may concern:

Be it known that I, ARCHIBALD BANNATYNE, residing at Waterbury, in the county of New Haven and State of Connecticut, have invented and produced a new and original Design in Clock-Dials; and I do declare the following to be a full, clear, and exact description of the same, reference being had to the accompanying drawing, which forms a part of this specification.

The accompanying drawing is a view in front elevation of a clock provided with a dial of my design.

The leading feature of my design is the representation of a druggist.

The dial A is of ordinary pattern, so far as time-indication is concerned. The druggist B, as here represented, is standing behind a counter, C, and in front of shelves, D, of drugs. He is represented as manipulating a pestle, E, which he holds in one hand, in a mortar, F, lo-

cated upon the said counter, at the farther end of which is a window, G, containing the druggist's sign H. The other surroundings are those of the drug-store.

25

I claim—

The design for a clock-dial herein shown and described, the same consisting of a clock-dial bearing the representation of a druggist with a pestle in his hand, a mortar, a counter upon which the mortar is placed and behind which the druggist stands, and shelves of drugs, druggists' signs in a window, and other appointments of a drug-store.

In testimony whereof I have signed this 35 specification in the presence of two subscribing witnesses.

ARCHIBALD BANNATYNE.
